PNEUMATIC HOLDER FOR WEFT ENDS

Gabriel C. Beatrice, Shrewsbury, and Kenneth J. Hall, Worcester, Mass., assignors to Crompton & Knowles Loom Works, Worcester, Mass., a corporation of Massachusetts

Application January 25, 1951, Serial No. 207,756

11 Claims. (Cl. 139—247)

1

This invention relates to improvements in pneumatic thread holders for the weft ends extending from reserve bobbins in a weft replenishing loom and it is the general object of the invention to provide a thread holder so constructed as to facilitate control of the weft ends of bobbins added to the magazine and also removal of a weft end corresponding to a transferred bobbin.

It is customary in weft replenishing looms of the bobbin changing type to provide some form of thread holder for the ends of the weft extending from the reserve bobbins stored in a magazine. Those forms of thread holders which operate pneumatically serve not only to tension the weft ends but are intended also to remove the weft end of a freshly transferred bobbin as soon as the thread of this bobbin is cut at the selvage. Where a number of threads enter the thread holder, however, the thread of a transferred bobbin may be held by neighboring threads and be prevented from being removed promptly.

It is an important object of the present invention to provide a thread collector having primary and secondary thread intake mouths the first of which may lead to a thread collector and the other of which is formed by angularly disposed members so related that the air moving into it will tend to dislodge the thread of a transferred bobbin from the other weft ends so that it can be drawn into the primary mouth and thence pass into a thread collector.

When fresh bobbins are being added to the magazine of a weft replenishing loom it is necessary that their weft ends be placed under control of the thread holder. It is a further object of the present invention to provide one of the aforesaid members with a mounting which will permit it to move from normally closed to an open position whereby the fresh weft ends can extend across the primary mouth and be drawn into the thread collector. This member is then returned to its normal position to assist in forming the previously mentioned secondary mouth.

It is a further object of the invention to make the movably mounted member in the form of a hinged cover which can be thrown back from its normal position and provide this cover with means for temporarily positioning the fresh weft ends so that they can be acted on by the column of air moving into the primary mouth.

It is a still further object of the invention to provide a separator to divide the weft ends into at least two groups one of which may be fine yarns and the other coarse yarns, and associate

2

this separator with a yieldable lock means for the hinged member effective to hold the latter in normal position but yieldable readily to permit the member to be swung to open position.

5 With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation of part of a loom having the invention applied thereto,

Fig. 2 is an enlarged plan view looking in the direction of arrow 2, Fig. 1,

15 Fig. 3 is a detailed vertical section on line 3—3, Fig. 2,

Fig. 4 is a side elevation looking in the direction of arrow 4, Fig. 2, parts being omitted,

Fig. 5 is a vertical section on line 5—5, Fig. 3.

20 Fig. 6 is an enlarged vertical section on line 6—6, Fig. 2, and

Fig. 7 is a diagrammatic view showing the hinged or cover member in two different positions.

25 Referring to Fig. 1, the loom frame 1 supports a reserve bobbin magazine M from which extend weft ends from reserve bobbins stored in the magazine but not shown herein. In the present instance these weft ends are shown as being arranged in front and back groups 2 and 3, respectively. These groups may be all of the same general type of weft, or one group can be composed of fine yarns and the other of coarse yarns, depending upon the character of fabric being woven.

30 The loom is provided with a lay 5 reciprocated backwardly and forwardly by the top or crank shaft 6 of the loom. The lay has a shuttle box 7 to receive a shuttle S. When the invention is applied to multicolor weft replenishing looms the shuttle shown will be one of several shuttles which are in action one at a time depending upon the pattern of the fabric.

35 The magazine is provided with the transerrer arm 10 which operates to effect renewal or replenishment of weft in the shuttle S when the latter is depleted of weft. During this renewal the thread end corresponding to the bobbin being transferred will move downwardly with the bobbin with respect to the other threads of its group.

40 The loom is provided with a thread collector C having a hollow cylinder 12 the interior of which is connected pneumatically to a hose or pipe 13 leading to an air pump 14 secured as at 15 to

55

the loom frame and having a piston 16 reciprocated by a lever 17 attached by connector 18 to the lay 5. As the latter swings back and forth the piston 16 will slide within the pump 14 and will act to create subatmospheric pressures within the collector C during backward movement of the lay. The pump is shown as one means for creating a partial vacuum within the cylinder 12, but the invention is not limited to use with the specific type of pump or thread collector shown in Fig. 1.

The upper end of the thread collector is provided with a plate 20 which fits the top of the cylinder 12 and is provided with an opening 21 which may be considered as a primary intake mouth for the threads of groups 2 and 3. The plate or top 20 may be secured to the collector in any approved manner, as by tie rods one of which is shown at 22. The tie rods are connected to a bottom 23 for the cylinder 12 and an upright 24 may be utilized to support the collector, as by the connection designated generally at 25 and attached to the top plate 20.

The matter thus far described may be constructed and operated in known manner, the collector C having subatmospheric pressures created therein at least during part of the loom cycle to draw a column of air down through the opening or primary intake mouth 21.

Mounted on the top 20 is a thread guide member designated generally at 30 having a horizontal base 31 and upwardly extending side wings 32 and 33 located respectively at the front and back. Lying over part of the base 31 is a deflector member 35 extending between the wings 32 and 33 and held in position by screws 36 which extend downwardly through slots 37 in the top 20. These screws also hold the thread guide 30 in position.

The base 31 has an opening 40 which registers with opening 21. The down bent end 42 of the deflector 35 preferably extends through the openings 21 and 40 and is provided with a plurality of prongs 43 the purpose of which is to prevent the weft threads from being drawn upwardly through the primary intake mouth back toward the magazine.

The base 31 has downwardly extending bearings 45 in which is rotatably mounted a rod 46 secured to a cover member 47. The rod 46 serves as a pivot or hinge for the cover member 47 located preferably below the base 31 of the thread guide 30. The cover member 47 extends upwardly as at 50 from the rod 46 and then laterally as at 51 between the wings 32 and 33 over the deflector 35. A stop 52 on the rod 46 by its engagement with the top 20 limits downward motion of the member 47 toward the deflector.

The deflector 35 is provided with an upwardly directed surface 55 leading to a surface 56 which curves toward the primary intake mouth as indicated for instance in Fig. 7. The upper part of the deflector 35 is provided with a surface 57 which extends more or less in the direction of member 47 when the latter is in the position shown in full lines in Fig. 7. Parts of the surfaces 56 and 57 form with the surface 58 on the under side of the member 47 a secondary intake mouth 59 through which the weft threads extend from the magazine toward the primary mouth. The sides of the secondary mouth are defined by the wings 32 and 33.

Under normal conditions the parts will be as shown in full lines in Fig. 7 with the weft ends from the magazine M entering the space below

the member 47 and above the deflector to pass through the secondary mouth 59 and into the primary mouth 21 and thence to the interior of the thread collector cylinder 12. The lower part 5 of a column of air approaching the secondary mouth will be deflected by surface 55 upwardly in a direction across or transverse of the weft threads for the purpose of disengaging the thread of a transferred bobbin from the other threads attached to the bobbins still in the magazine M. When this thread, shown at T in Fig. 7, is subsequently cut the upwardly moving part of the column of air approaching the secondary mouth will lift and detach it from the remaining threads 10 so that it can move freely toward the primary mouth and collector.

When new bobbins are added to the magazine it will be necessary to effect entry of their weft threads into the collector. This will be done by 20 swinging the pivoted member 47 from the full line to the dotted line position shown in Fig. 7 and then laying the fresh weft ends across the top of the deflector 35 close to the primary mouth 21 into which they will be drawn because of the 25 subatmospheric pressures existing within the thread collector. These new threads will be guided toward the primary mouth by the wings 32 and 33. After the new weft ends have been correctly placed in the primary mouth the cover member 47 will be returned to the full line position shown in Fig. 7 and will again reestablish the secondary mouth in cooperation with the thread deflector and the side wings 32 and 33.

If desired provision may be made for yielding locking member 47 in the full line position shown 30 in Fig. 7. As shown in the drawings this locking means comprises an upright separating post 65 secured to the deflector member 35 preferably midway between the walls 32 and 33. The member 47 is provided with a slot 66 in the right end of which the top of the post 65 will be located when the cover or member 47 is in its normal position. A leaf spring 67 is secured as at 68 to the member 47 and extends along and above the slot 66 and is of such length that it will be bent into the slot by the top of post 65 when the cover member 47 is turned in a clockwise direction from its full line position Fig. 7. When the cover member is returned to its normal position the end of the spring 67 adjacent to the post 68 will be engaged and deflected by the latter until the cover is in low enough position to permit the spring lock 67 to assume the position shown in Figs. 3 and 7.

The post 65 is shown herein as being in position to separate the weft ends of the groups 2 and 3 so as to prevent the collection of too large a group of weft ends at any one point along the width of either the secondary or the primary mouths. The yielding lock spring 67 not only prevents accidental displacement of the cover member 47 but may also serve to resist upward movement of the cover member by a column of air rising along surface 55 and directed against surface 58.

While the cover member 57 may be swung from the full line to the dotted line position, Fig. 7, by being grasped by the operator it may be desirable to provide a simple means of opening the cover by a mere movement of the hand, in which event the rod 46 may be bent to form a handle 70 which will be more or less upright as shown in Fig. 7 when the cover member 47 is in normal position. When the operator is placing new bobbins in the magazine and has hold of several

fresh weft ends or threads a movement of his hand to the right in Fig. 7 will draw the threads away from the magazine and at the same time effect rocking of the cover member to dotted line position due to engagement of his hand with the upright rod or handle 70. Thus, by a single motion of the hand the cover can be opened and the new weft ends drawn down across the deflector 35 between the wings 32 and 33 to a position where they can be drawn pneumatically 10 into the primary intake mouth 21. When the new weft ends are drawn across the primary mouth they may if desired be permitted to fall between spacing pins or guides 11 projecting upwardly from the members 47, see lines, Fig. 7.

From the foregoing it will be seen that the invention sets forth a simple form of pneumatic thread holder having primary and secondary threads intake mouths for the weft ends extending from the reserve bobbin magazine. The secondary mouth is formed in part by the deflector member 35 and the cover member 47, and the latter is so mounted that it can be swung back to expose the primary mouth for the reception of weft ends of bobbins freshly inserted into the magazine. The surface 55 of the deflector directs part at least of the column of air moving in a direction from the magazine toward the secondary mouth in an upward direction to detach a thread corresponding to a freshly transferred bobbin from the remaining threads so that it can be drawn readily through the secondary and primary mouths into the thread collector. Stop means are provided to limit movement of the cover member 47 toward the deflector to insure maintenance of the secondary mouth when the cover member is in its normal position. The cover 47 is associated with a handle or the like 70 which can be readily moved by the hand of an operator when fresh threads are being placed in position to be drawn into the primary mouth. The spacing post 65 not only holds the groups 2 and 3 of weft ends separated from each other but is also associated with a yielding lock means which normally acts to hold the cover member 47 in normal position shown in full lines in Fig. 7.

Having thus described the invention it will be seen that changes and modifications of the foregoing specific disclosure may be made without departing from the spirit and scope of the invention.

What is claimed as new is:

1. In a pneumatic thread holder for a group of threads extending from a reserve bobbin magazine, means defining a primary thread intake mouth within which subatmospheric pressures exist and into which the threads extend, an air deflector directing air moving from the magazine toward the intake mouth in an upward direction across the threads, and a member pivoted on the thread holder extending over said primary mouth and said deflector spaced from the latter and forming therewith a secondary intake mouth for the threads located between the magazine and said primary mouth, said member being swingable away from said deflector and primary mouth to uncover the latter for entry thereinto of threads deposited on the deflector and extending from bobbins in the magazine.

2. The structure set forth in claim 1 wherein a stop on said member engages a stationary part of said thread holder to limit pivotal movement of said member toward said deflector.

3. The structure set forth in claim 1 wherein

5 a handle is secured to and extends upwardly from said member and is located beyond said secondary mouth with reference to the magazine and affords means by which said member may be swung away from said deflector.

4. In a pneumatic thread holder for a group of threads extending from a reserve bobbin magazine, means defining a primary thread intake mouth within which subatmospheric pressures exist and into which the group of threads extend, a member pivoted on the thread holder normally extending over the primary mouth, means on the holder cooperating with said member to define a secondary mouth located between the magazine and the primary mouth, and an air deflector between the magazine and the secondary mouth effective to direct a column of air moving from the magazine toward the secondary mouth in an upward direction toward said member and across the threads entering the secondary mouth to detach a free thread from the other threads in the secondary mouth and facilitate movement of said free thread toward said primary mouth.

5. In a pneumatic thread holder for a group of threads extending from a reserve bobbin magazine, means defining a primary thread intake mouth within which subatmospheric pressures exist, a member on the thread holder extending over the primary mouth and toward the magazine, means on the holder cooperating with said member defining with the latter a secondary mouth located between that part of the member adjacent to the magazine and the primary mouth, and an air deflector between the magazine and the secondary mouth effective to direct a column of air moving from the magazine toward the secondary mouth in an upward direction toward said member and across threads extending from the magazine into said mouths to detach a free thread from the other threads in the secondary mouth and facilitate movement of said free thread toward said primary mouth.

6. In a pneumatic thread holder for a group of threads extending from a reserve bobbin magazine, means defining one side of a thread intake mouth into which said group of threads extend and within which subatmospheric pressures exist, said means including a part extending from said one side of said mouth toward the magazine, and a deflector defining the opposite side of said mouth extending from the latter toward the magazine and inclined away from said part effective to direct a column of air moving from the magazine toward said mouth in a direction toward said part of said means and across said group of threads to detach a free thread from said group and facilitate entry of said free thread into said mouth, said part of said means directing air toward said mouth.

7. In a pneumatic thread holder having a thread intake mouth within which subatmospheric pressures exist and into which extend threads from the reserve bobbins of a weft replenishing loom magazine, a thread guide intermediate said mouth and magazine formed with upright thread guiding wings at the sides of the threads, and a cover member pivoted on said thread guide to swing about an axis transverse of the threads, said cover member when in normal position being over said mouth and the parts of the threads adjacent to said mouth and between said wings, said cover being movable angularly about said axis away from said wings to an inoperative position to uncover said mouth to permit

entry thereinto of threads leading from the magazine and extending between said wings.

8. The structure set forth in claim 7 wherein a handle is secured to said member and extends upwardly above said wings and affords means by which said member can be moved angularly about said axis.

9. The structure set forth in claim 7 wherein a deflector between said wings and under said cover member is effective to direct a column of air moving in a direction from the magazine toward said mouth and between said wings in an upward direction across said threads.

10. The structure set forth in claim 7 wherein spacing guides on the cover member are effective when the latter is in the inoperative position thereof to hold threads extending from the magazine and between said wings in alignment with said mouth.

11. The structure set forth in claim 7 wherein a thread spacer is located intermediate said wings and yielding spring lock means cooperates with said spacer to hold said cover member in normal position.
